UNITED STATES PATENT OFFICE.

YAICHIRO SHIBA, OF SAN JOSE, CALIFORNIA.

COMBINED FINGER RING AND CORD CUTTER.

Application filed November 17, 1925. Serial No. 69,577.

This invention relates to improvements in combined finger rings and cord cutters of the type disclosed in my U. S. Letters Patent No. 1,521,051, granted Dec. 30, 1924.

5 The main purpose of the present invention is to provide a combined ring and cord cutter arrangement in which the cutting means will at all times, be concealed but is ready for operation without requiring the slipping 10 of a catch or movement of any operating member, it only being necessary to bring the piece of string or cord to be cut against the end or side of the setting in order to gain 15 access to the cutter.

15 The ring of this invention is capable of being made small and in more compact form, without detracting from the efficiency of the cutting means and is also subject to being made more decorative and ornamental, 20 particularly due to the ingenious construction and arrangement of the mechanism employed.

With the above mentioned and other objects in view, the invention consists in the 25 novel construction and combination of parts hereinafter described, illustrated in the accompanying drawings, and set forth in the claim hereto appended, it being understood that various changes in the form, proportion, 30 size and minor details of construction within the scope of the claim may be resorted to without departing from the spirit or sacrificing any of the advantages of the invention.

Referring to the drawing:

35 Fig. 1 represents a perspective view showing the manner of using the ring as a cord cutter.

Fig. 2 represents a top plan view of the 40 ring of this invention.

Fig. 3 represents a top plan view with the set removed.

Fig. 4 represents a side elevation of the 45 ring.

Fig. 5 represents a side elevation of the ring showing the position of the parts assumed when operating it to cut string or 50 cord.

Fig. 6 represents an enlarged sectional view of the ring.

55 Fig. 7 represents a bottom plan view of the setting showing the cutting means applied thereto.

In carrying out the invention there is provided an ordinary ring body portion 1 having a base 2 on its upper side. Mounted on this base is a setting 3 which, in the press-

ent instance, is shown of a diamond shape. This setting 3 is in the nature of a flat plate and the ring is similar to an ordinary signet ring. Projecting downward from the under 60 side of and suitably fastened to the setting 3 is a lug 4 which extends loosely into an opening 5 provided in the base 2. A hinge pin 6 is inserted through the base laterally and through the lug 4 to hingedly connect 65 the setting with the ring. The lug 4 is between the ends of the setting and to provide for holding the setting close against the base 2 at all times, an expansion helical spring 7 is mounted between the base and setting, 70 the ends of said spring being engaged in registering recesses 8 and 9 provided in the base and setting respectively. Certain ends or 75 sides of the base and setting are beveled as at 10 so as to provide a shallow notch into 70 which a piece of string or cord, as shown at A, may be moved. A cutting knife 11 is secured by fastenings 12 to the under side of the setting 3 and is adapted to engage in a recess or groove 14 formed in the base 2. 80 The setting may have any suitable decoration, for example, a jewel, as shown at 14'.

The setting normally lies close to the outer side of the base so that the spring lock and knife are entirely concealed. The ring therefore appears at all times as an ordinary ring and its ornamental value is therefore enhanced.

To cut a piece of string or cord, when the ring is worn upon the hand, as shown in 90 Fig. 1, the operator brings a piece of cord against the beveled faces 10 at one end of the ring and the pressure of the cord against the setting, causes the setting to rock on its pivot 6 and the outer end thereof to lift upwardly against the action of the spring 7. This raising of the setting, lifts the knife 11 95 out of the groove 14 and as the cord is moved between the setting and base, it will encounter the knife and be severed. The knife is arranged diagonally so as to produce a better cutting action when the cord is drawn over its sharpened edge. The ring of this invention is at all times ready for the cutting operation, it being unnecessary to operate a catch or any operating member to prepare the cutting mechanism for operation. When the string or cord is withdrawn, the spring 7 returns the setting 3 to closed position, lying in close engagement 100 with the base. Heretofore in the art it has been necessary to provide some means for 110

holding the setting closed and close against the base, in order to conceal the cutting means and to release this holding means when preparing the ring for a cord cutting operation. I am also aware of cord cutting rings where springs maintain the setting raised so as to permit of access to the cutter, but in rings of this type, the cutting mechanism is revealed and spoils the appearance of the ring. The present invention therefore, does away with the objections which were present in rings heretofore made and simplifies the construction and operation of said rings, to say nothing of lessening the cost of manufacture thereof.

I claim:

A combined finger ring and cord cutter comprising a ring body portion having an opening therein and provided with a groove,

the ends of which terminate short of the edges of the body, a member having a lug depending therefrom between its ends and sides and extending into said opening, a pin extending through the body portion and said lug, said body portion and member having registering recesses therein in their opposed faces, a spring mounted in the recesses and holding the said member flat against and parallel with the body portion, a knife carried by said member and extending into said groove, said knife being normally concealed between the body portion and said member, the opposed faces of the body portion and said member at certain corresponding edges thereof being bevelled to permit of insertion of a cord between said member and body portion.

YAICHIRO SHIBA.
